RECREATION AND AMUSEMENT MACHINE

Filed March 21, 1929

UNITED STATES PATENT OFFICE

AMBROSE H. EVANS, OF HUTCHINSON, KANSAS

RECREATION AND AMUSEMENT MACHINE

Application filed March 21, 1929. Serial No. 349,823.

The device forming the subject matter of this application comprises pendulum paddles adapted to be kicked, punched, or struck by a ball that is bowled, pitched, or impelled by a cue. One object of the invention is to provide novel means whereby the force imparted to the paddles may be indicated. Another object of the invention is to provide a novel mechanism for releasing the means whereby the indicating is accomplished.

It is within the province of the disclosure to improve generally and to enhance the utility of devices of that sort to which the present invention appertains.

With the above and other objects in view, which will appear as the description proceeds, the invention resides in the combination and arrangement of parts, and in the details of construction hereinafter described and claimed, it being understood that changes may be made in the precise embodiment of the invention herein disclosed, within the scope of what is claimed, without departing from the spirit of the invention.

In the accompanying drawings:—

Figure 1 shows in top plan, a device constructed in accordance with the invention, parts being broken away;

Figure 2 is a side elevation wherein parts are broken away;

Figure 3 is a front elevation, parts being broken away, and parts being in section;

Figure 4 is an elevation disclosing the slide and attendant parts, the releasing circuit being shown in diagram;

Figure 5 is an elevation of the structure disclosed in Figure 4, with some added parts in section;

Figure 6 is a fragmental elevation showing a modification in the paddle.

The device forming the subject matter of this application may be operated in a variety of ways, as has been stated hereinbefore.

In order to simplify the description, however, it will be presupposed that the device is to be operated by bowling, and, therefore, the numeral 1 has been used to designate the bed of a bowling alley forming part of a support, designated as a whole by the letter S.

On each side of the bed 1 there is a gutter 2.

A forward frame 3, a rear frame 4, and an intermediate frame 5, are mounted vertically on the bed 1, and are connected by side beams 6. The intermediate frame 5 is somewhat higher than the forward frame 3 and the rear frame 4 of the support S. 55

On the rear end of the support S there is a hood 7 which overhangs a transverse gutter 8 mounted on the support S. At its outer end, the gutter 8 communicates with a downwardly and forwardly inclined chute 9. An upwardly and rearwardly inclined platform 10 extends from the intermediate frame 5 to the hood 7. When a ball is rolled along the bed 1 of the alley, the ball actuates certain instrumentalities to be described hereinafter and the ball rolls up the platform 10 into the transverse gutter 8, the hood 7 preventing the ball from shooting out of the machine at the rear end of the support S. 60 The ball rolls along the transverse gutter 8 into the chute 9 and by the chute the ball is delivered at the point where the bowling is going on, and at such a height that the bowler 70 does not have to stoop to pick up his balls. 75

Depending brackets 11 are mounted on the upper portion of the forward frame 3. Vertical paddles 12 are pivotally mounted intermediate their ends at 14 on the brackets 11. 80 Buffers 15 are adjustably mounted on the rear surface of the paddles 12.

There is a radius arm 16 for each of the paddles 12, the forward end of the radius arm being pivotally mounted at 17 on the 85 brackets 11. The radius arm 16 has an enlarged head 18 at its rear end, and the head 18 rests on the horizontal portion 19 of a cross piece 20 embodied in the intermediate frame 5 and including a vertical flange 21. 90 A replaceable buffer 22 is mounted in the head 18 of the radius arm 16. A buffer 23 is mounted on the lower surface of the radius arm 16 and is so placed as to cooperate with the buffer 15 on the paddle 12. A weight 24 95 is adjustably mounted at 25 on the radius arm 16. It may here be observed that an equivalent device, designated by the numeral 40 may be used to mount the buffer 15 on the paddle 12. 100

Rack bars 26 are secured at their lower ends, as indicated at 39, in the horizontal portion of the cross piece 20. The rack bars 26 extend upwardly along the vertical flange 5 21 of the cross piece 20 and have their upper ends mounted on the top portion of the intermediate frame 5. Slides 27 are mounted for vertical reciprocation on the guides 28 that extend between the part 19 of the cross piece 20 and the upper portion of the intermediate frame 5. The slides 27 are provided with buffers 29 on their lower ends, and these buffers cooperate with the buffers 22 of the radius arms 16.

15 Each slide 27 has a lateral pointer 30 adapted to cooperate with a vertical scale 31 on the intermediate frame 5, there being as many of these scales as occasion may require. The slide 27 carries a spring dog 32 which is 20 forked at 33 to straddle and engage the rack bar 26. Any suitable means may be provided for disengaging the dog 32 from the rack bar 26. By way of illustration, but not of necessity, the dog 32 has an armature 34 25 adapted to be attracted by an electro-magnet 35 on the slide 27. Conductors 36 lead from the magnet 35 to brushes 37 on the slide 27, the brushes making electrical contact with the guides 28, the guides being located in a 30 circuit 38 that includes a switch 41 and a source 42 of electrical energy, the switch being under the governance of an operator.

In practical operation, a ball (not shown) impelled along the bed 1 of the alley, in any 35 suitable way, strikes one of the paddles 12 and swings the lower end of the paddle backwardly and upwardly, the buffer 15 on the paddle cooperating with the buffer 23 on the radius arm 16, to swing the rear end of the 40 radius arm upwardly, the radius arm causing the slide 27 to move upwardly on the guides 28. The end 33 of the dog 32 cooperates with the rack bar 26 to hold the slide in any position to which it may have been driven upwardly, the pointer 30 on the slide coating with the scale 31 to indicate the force with 45 which the paddle 12 was struck. The operator can close the switch 41, thereby energizing the magnet 35 and retracting the dog 32 from engagement with the rack bar 26. Then the 50 slide 27 will move down on the guides 28 until the buffer 29 on the slide cooperates with the buffer 22 in the head 18 of the radius arm 16, the head of the radius arm resting on the 55 part 19 of the cross piece 20.

In the event that the operator wishes to punch or kick the paddle 12, instead of hitting it with a ball, it may be expedient to put a cushion 43 on the paddle 44, as shown in 60 the modification depicted in Figure 6.

Having thus described the invention, what is claimed is:—

1. In a device of the bowling-alley type, a support, guides on the support, vertically- 65 movable slides mounted to reciprocate on the

guides, means wherewith the slides cooperate to form an indicator, mechanism for holding the slides in adjusted positions on the guides, said mechanism embodying a latch, an electro-magnet on the slides, the latch being responsive to the electro-magnet, brushes on the slides and engaging the guides, a circuit including the guides, the brushes and the electro-magnet, a switch in said circuit and under the control of an operator, a source of electric energy in said circuit, and impact-operated means for actuating the slides. 70

75

2. In a device of the class described, a support, a paddle pivoted to the support, a radius arm resting on the support and pivoted to the support, the radius arm being disposed in the path of the paddle, a slide mounted for reciprocation on the support and operable by the radius arm, mechanism for holding the slide after it has been raised by the action of the radius arm, means under the control of an operator for releasing said mechanism, a weight, and means for mounting the weight in adjusted positions on the radius arm. 80

85

In testimony that I claim the foregoing as 90 my own, I hereunto set my hand.

AMBROSE H. EVANS.
